UNITED STATES PATENT OFFICE

138,195

DESIGN FOR A TOY WAGON

Tom Duffy, Detroit, Mich., assignor to Montgomery Ward & Co., Incorporated, Chicago, Ill., a corporation of Illinois

Application August 11, 1943, Serial No. 110,890

Term of patent 14 years

(Cl. D34—15)

To all whom it may concern:

Be it known that I, Tom Duffy, a citizen of the United States, residing at Detroit, in the county of Wayne and State of Michigan, have invented a new, original, and ornamental Design for a Toy Wagon, of which the following is a specification, reference being had to the accompanying drawing, forming a part hereof.

The figure is a perspective view of a toy wagon showing my new design.

I claim:

The ornamental design for a toy wagon, as shown.

TOM DUFFY.
